DESIGN FOR A DISPLAY CONTAINER OR SIMILAR ARTICLE

John C. O. Ritzenthaler, Montclair, N. J.

Application May 14, 1936, Serial No. 62,639

Term of patent 3½ years

To all whom it may concern:

Be it known that I, John C. O. Ritzenthaler, a citizen of the United States and a resident of Montclair, in the county of Essex and State of New Jersey, have invented a new, original, and ornamental Design for a Display Container or Similar Article, of which the following is a specification, reference being had to the accompanying drawing, forming part thereof.

The figure is a perspective view of a display container showing my new design.

I claim:

The ornamental design for a display container or similar article substantially as shown.

JOHN C. O. RITZENTHALER.
